ABSTRACT

An electrical switch includes sets of contacts and countercontacts, one set being mounted on a movable carrier which is moved by a pneumatic cylinder and piston arrangement in one direction and by return springs in the other direction. The air inlet into the pressure chamber of the pneumatic arrangement is provided with a ball valve which allows only a slow flow of air into the working chamber during movement of the contacts towards engaging position but allows rapid movement to disengaging position.

ELECTRICAL SWITCH APPARATUS.

BACKGROUND OF THE INVENTION

Field of the Invention

The invention relates to an electrical switch apparatus.

SUMMARY OF THE INVENTION

The purpose of the present invention is to make a switch apparatus, particularly a switch contactor, which being simple and inexpensive in construction, can be used even in areas where there is risk of explosion and similar situations and applications, and which has a considerably longer life expectancy than hitherto.

According to the invention, there is provided an electrical switch apparatus comprising a plurality of contacts and countercontacts which are connectable to electrical cables and which correspond to one another, and an actuating device associated with these contacts and countercontacts, with whose help a relative movement is produced between the contacts and countercontacts in order to bring them together or to separate them, the actuating device including a pneumatic or hydraulic work chamber, whose movable transmission member is fixed by an intermediate member to a movably guided carrier for the contacts or the countercontacts and upon whose actuation the movement of the carrier corresponding to the relative movement between contacts and countercontacts is effected with the help of the pressure medium through the intermediate member.

The pneumatic or hydraulic work chamber can be a single-action or double-action cylinder, and a work piston can, for example, be movably guided to and fro in the work cylinder, or a diaphragm or roll diaphragm can be used as a transmission member.

The arrangement according to the invention, which is best suited for switching and controlling motors, has the advantage that it can be used even in areas and situations where there is risk of explosion, as instead of electrical or magnetic actuation, the device is operated pneumatically or hydraulically. The life duration of the new apparatus is considerably larger than in known comparable arrangements, as in the latter the actuating magnet is destroyed, damaged or worn out after a number of switch operations, and the airgap becomes correspondingly narrower. In this way the life duration can be increased five to 10 times, and the device is correspondingly more reliable. Further, the bounce of the contacts in the new device is considerably reduced. Finally, there is the further advantage that, contrary to known devices, a higher actuating force can be employed; this force is constant, leading in the final analysis to a reduction in switching delay. When the subject matter is designed as a so-called contactor with double interruptor, the life duration is increased as a result of the uniform distribution of oxidation on the pairs of contacts.

BRIEF DESCRIPTION OF THE DRAWINGS

Embodiments of the invention will now be described, by way of example, with reference to the accompanying drawings.

In the drawings:

FIG. 1 shows a first embodiment of the device according to the invention in a diagrammatic side view; and

FIG. 2 shows a part of a second embodiment of the device according to invention in side view in a vertical cross section.

DESCRIPTION OF THE PREFERRED EMBODIMENTS

In FIG. 1 of the drawings contacts 1, 2 are provided on carrier 3, designed as a longitudinal rod-shaped member which, in the embodiment shown in FIG. 1 of the drawings, has the form of a so-called contactor with double interruptor, and carries pairs of opposed contacts 1 and 2. Naturally, several pairs of such contacts can be provided. With each pair of contacts 1 and 2 there is in the present case associated a pair of countercontacts 4 and 5, which are combined in pairs, which are sta-

tionarily arranged in the casing. On the side of carrier 3 facing the actuating device, a support plate or rod 6 is provided, on which engage return springs 7, 8, such as compression springs, associated with the carrier, the other ends of said springs being supported on a part 9 of the casing.

In order to actuate the contacts and countercontacts, that is in order to produce the relative movement between the contacts and countercontacts, which serves to apply said contacts and countercontacts to one another or to separate them, a pneumatic or hydraulic work chamber 10 is provided according to the invention as an actuating device, said work chamber 10 being designed as a single-action or as a double-action chamber. In the case of the single-action chamber as in the embodiment shown in the drawings, the introduction of the pressure medium into the work chamber through a pipe 11 is associated with the movement for applying the contacts and countercontacts to one another, while, in order to produce the opposite movement, one or more return springs is or are associated with a transmission member 13 within the work cylinder. Such a return spring may for example be arranged inside the cylinder, and act directly on the transmission member. The springs 7, 8 already mentioned, or only one such spring, may be used as a return spring. Finally, return springs may be associated both with the transmission member and with the contact carrier, that is a combination of the above embodiment may be provided. In the case of the double-action chamber, the return springs may be eliminated or, if necessary, weaker springs may be used. As the drawing shows, 10 the work chamber may be a cylinder and have as a transmission member a piston 13 which is movable to and fro inside the cylinder. In the single-action pneumatic cylinder shown in the drawing, 14 is the exhaust. However, other types of actuating devices may be used. In all cases the actuating device of 15 the carrier is parallel to that of the transmission member of the work chamber, or they coincide. The transmission member is rigidly connected to the movably guided contact carrier by the rod 15.

The actuating device, the contacts and the countercontacts 20 are housed with their associated actuating and transmission components, in a casing shown only diagrammatically at 16; the space taken up can be kept small.

In the embodiment shown in FIG. 1 of the drawings, springs 25 7 and 8 are designed as compression springs; likewise, a spring acting on piston 13 might be designed as a compression spring. The springs of the embodiment shown tend to separate the contacts and countercontacts, while the pressure medium tends to do the opposite, that is to bring the contacts and countercontacts together. However, the springs may of course alternatively be used as tension springs, which tend to bring the contacts and countercontacts together, while in this case the pressure medium has the purpose of separating them. When the springs are designed as tension springs, the contacts 30 1 and 2 being arranged on the other side of the countercontacts 3 and 4, relative to the view in the drawing, provision can be made for the springs to separate the contacts and countercontacts, and for the pressure medium to bring them together. By interchanging the air feed and evacuation pipes, finally, other variants can be formed. All these variants are intended for special examples of use.

In FIG. 2 of the drawings a single-action pneumatic cylinder 20 is used within which the piston 21 carrying a sealing ring 23 is movable to and fro according to arrows 22. The pressure air is introduced within the cylinder through the channels 24, 25. When air is entering through these channels, ball 26 rests on its seat 28, but there is not produced a sealing effect, since the ball 26 does not perfectly adhere to its seat, represented by the bush or sleeve 28. Between ball 26 and its seat 28 there remains a radially directed free space or interspace 29 through which pressure air coming from channel 25 passes through channel 27 into the chamber 30 of the single-action pneumatic cylinder in order to move the piston and its piston rod 31 in downward direction according to arrow 22a. Thereby, the carrier 32 which is connected with the head 33

of the piston rod 31 by a projection 34 engaged into the groove 35 of the head 33 is moved also downwards according to arrow 22a and thus the contacts and countercontacts are applied one against the other. The purpose of the ball 26 which is subjected to the action of the spring 36 is to reduce the cross section of the passage of pressure air from channel 25 to channel 27 as much as possible, in the manner of a throttle. By this means the contact carrier is prevented from moving with too great a speed downwards in direction of the closed position of the contacts, whereby undesired vibrations of the contacts could arise. When the contacts are to be opened, then pressure is relieved, for example, by means of a valve not shown, connected with channel 24 and this latter channel is connected with the atmosphere. Then, pressure spring moves piston rod 31 and piston 21 in upward direction according to arrow 22b and the air contained in chamber 30 is expelled through channels 27, 25 and 24, whereby ball 26 is lifted from its seat so that the air may pass unhindered and with full speed through these channels.

Although my invention has been illustrated and described with reference to the preferred embodiments thereof, I wish to have it understood that it is in no way limited to the details of such embodiments, but is capable of numerous modifications within the scope of the appended claims.

Having thus fully disclosed my invention, what I claim is:

1. An electrical switch apparatus comprising sets of contacts and countercontacts which are connectable to electrical cables and which correspond to one another, and an actuating device associated with these contacts and countercontacts for producing a relative movement between the contacts and countercontacts in order to bring them together or to separate them, the actuating device including a fluid pressure work chamber containing a pressure medium, a movably guided carrier for one of the sets, said actuating device having a movable transmission member connected to said movably guided carrier on whose actuation the movement of the carrier corresponding to the relative movement between contacts

and countercontacts is effected with the help of the pressure medium, wherein the fluid-pressure work chamber is provided with an air inlet, and a throttle in said air inlet for reducing the speed of the air entering the work chamber, and wherein the 5 throttle comprises a ball and a spring acting on the ball and a seat associated with said ball, a passage with small cross section between said ball and said seat which passage connects said inlet with said work chamber, whereby the pressure air issuing from said work chamber upon disengaging the said contacts from said countercontacts lifts said ball from its seat.

2. A switch apparatus according to claim 1, wherein the fluid-pressure work chamber is a single-action cylinder.

3. A switch apparatus according to claim 2, wherein the introduction of the pressure medium into the work cylinder is 15 associated with the movement for bringing together the contacts and countercontacts, and return spring means associated with the transmission member in order to produce the opposite movement.

4. A switch apparatus according to claim 1, wherein the 20 fluid-pressure work chamber is a double-action work cylinder.

5. A switch apparatus according to claim 1, wherein the contacts are arranged on the carrier whose direction of movement is parallel to that of the transmission member of the work chamber while the countercontacts are fixed.

25 6. A switch apparatus according to claim 1 wherein said sets constitute a contactor with double interruptor.

7. A switch apparatus according to claim 3, wherein the carrier for the movable contacts is a longitudinal rod-shaped member, whose longitudinal medial axis coincides with the 30 direction of movement of the transmission member, and which carries pairs of opposed contacts and, on the side facing the piston, a support plate or rod, on which the return spring means engages.

8. A switch apparatus according to claim 1, wherein a work 35 piston is guided to move to and fro in a work cylinder constituting the work chamber, said piston constituting the movable transmission member.
